UNITED STATES PATENT OFFICE.

HENRY WISCHHUSEN, OF MALDEN, AND EMILY A. WISCHHUSEN, OF EVERETT,
MASSACHUSETTS.

GAME BOARD.

Application filed January 28, 1922. Serial No. 532,521.

To all whom it may concern:

Be it known that we, HENRY WISCHHUSEN and EMILY A. WISCHHUSEN, citizens of the United States, residing at Malden and 5 Everett, respectively, in the county of Middlesex and State of Massachusetts, have invented certain new and useful Improvements in Game Boards, of which the following is a specification.

10 The object of this invention is the devising of a game board which shall bear the representations of substantially all the cards of a deck, and which can be played by means of counters or "men" controlled by dice or other 15 number designating means.

The game to which we show the invention as applied is of the well-known parcheesi type, the various movement-spaces on such 20 a game-board bearing the representations of the different members of a deck of cards.

The drawing forming part of this specification illustrates a game-board embodying our invention, a part thereof being represented as broken away.

25 As in a parcheesi game, the board 1 is provided with a central space 2 usually termed "home," and spaces 3 at the corners for the counters 4 before entering their turn upon the course, and for the dice 5.

30 Between the home 2 and each edge of the board is a series of blank spaces 6 having at each side of such row of spaces 6 an equal number of spaces 7 each bearing the representation of some one of the cards of a deck,

35 the number of the spaces being such that, including the spaces between adjacent corners of the rows 7 in which is located the representation of a card 9, every one of the entire fifty-two is shown. We also indicate in the 40 home 2 the "joker" 10, in order to provide for the deck of fifty-three which many players desire to have.

Instead of the four men usually apportioned to each player in parcheesi, we prefer 45 to provide five, but in many other ways the game is similar thereto. The men are entered on the spaces bearing the ace nearest each player, each man or counter 4 being allowed to be entered upon such space when

his player has thrown a pair of dice which 50 show five spots. After a counter has thus been entered it can be moved to other spaces in accordance with further throws of the dice. For example, if a pair of dice turn up a four and a five, the entered counter can be 55 moved along nine spaces, or if the player has two counters entered, he can move one four spaces and the other five; and so on around the board until home is reached. In these respects, the game is played substantially 60 like parcheesi, the main difference consisting in the scoring.

No man can enter a space already occupied, and if the number thrown would bring a man to an occupied space, then it must be 65 returned.

The principle of the game is to score as often as possible before the men reach the home path 6, the degree of each score depending upon which of the various cards the 70 men have rested. What we prefer is to have the scoring done according to the rules of poker. For example, the score for a royal flush 100, straight flush 90, 4 of a kind 80, full house 70, flush 60, straight 50, etc. 75

The player having man on ace of hearts, another on ace of diamonds and another on ace of clubs has 3 of a kind and is entitled to score 40.

The player first bringing all his men home 80 concludes the game, and scores are to be added to decide the winner.

What we claim is:

A game board comprising a central home space, and rows of spaces surrounding and 85 leading to the same, certain of said spaces bearing the representations of playing-cards employed in the game of poker, whereon counters are moved according to throws of dice to rest upon certain of said spaces, said 90 spaces being held to score an amount relative to that which playing cards score in the game of poker.

In testimony that we claim the foregoing invention, we have hereunto set our hands 95 this 27th day of January, 1922.

HENRY WISCHHUSEN.
EMILY A. WISCHHUSEN.
